MOLD FOR A MOUSSE OR THE LIKE

Cyril Alfred Melling, London, England, assignor to Lever Brothers Company, New York, N.Y.

Filed Apr. 6, 1970, Ser. No. 22,255

Claims priority, application Great Britain Oct. 9, 1969

Term of patent 14 years

Int. Cl. D7—99

U.S. Cl. D44—1

FIG. 1 is a top perspective view of a mold for a mousse or the like showing my new design;

FIG. 2 is a side elevational view; and

FIG. 3 is a bottom plan view.

I claim:

The ornamental design for a mould for a mousse or the like, substantially as shown.
